HOLDER FOR ROLLS OF PAPER

Filed March 26, 1929

UNITED STATES PATENT OFFICE

JOHN F. DUBY, OF BOSTON, MASSACHUSETTS

HOLDER FOR ROLLS OF PAPER

Application filed March 26, 1929. Serial No. 349,998.

This invention relates to holders for rolls of paper such as toilet paper or the like, and its principal object is to provide a convenient holder of improved construction comprising a small number of parts which are economical to manufacture and easy to assemble, removably to support a roll of paper in vertical position.

Recommended embodiments of the invention are illustrated in the accompanying drawing, in which:

Fig. 1 is a side elevation of a preferred form of holder;

Fig. 2 is a central transverse section through the holder of Fig. 1; and

Figs. 3 and 4 are elevations, partly in section, of modified forms of holders.

The devices herein illustrated are particularly adapted to be mounted on a wall to hold individual rolls of toilet paper. The holder of Figs. 1 and 2 comprises a horizontal base plate 5 having a bracket arm 6 attached as by screws 7 to the wall 8; an upright cylinder or core 9 of wood or other suitable material fastened to the plate 5 as by a screw 10, and having an axial recess 11 extending downwardly from its upper end; and a top or cover plate 12 having a depending tubular stem 13 received within the recess 11. Locking means are preferably provided releasably to secure the cover plate upon the cylinder, and such means may comprise a leaf spring 14 extending vertically along the surface of the cylinder 9 and having its lower end 15 bent under the cylinder and fastened by the screw 10, and a detent 16 at its upper end projecting inwardly through registering apertures 17 and 18 in the core 9 and stem 13 respectively. The locking detent 16 may be released by inserting a key 19 into the tubular stem to spring the detent outwardly.

The roll of paper 20, having the customary interior cardboard tube 21 loosely receiving the cylinder or post 9, rests in vertical position upon the base plate 5 and is secured against casual displacement by the locked cover plate 12. The paper may readily be unrolled by hand, yet the rotation of the paper roll is resisted by gravitational pressure between the bottom edges of the rolled pa-

per and the plate 5, so that the unrolling of more paper than is required at any given time or accidental unrolling of the paper by casual contact is prevented. The cover plate of the holder may readily be removed as aforesaid to permit the substitution of a fresh roll, and for this purpose the clearance between the cylinder 9 and the roll tube 21 should be sufficient to allow retraction of the detent 16 from the stem aperture 18.

In Fig. 3, the base plate 22 is fastened to the wall by means of rubber suction cups 23, and has a fixed upstanding spindle 24 loosely received within an axial recess 25 in the base portion of the core 26; and the cover plate 27 is secured on the upper end of the core as by a screw 28. In this modification the holder parts are separated by lifting the top plate and core as a unit off the spindle 24, to permit the insertion or replacement of a paper roll.

In the further modification shown in Fig. 4, the post 29 is mounted upon the base plate 30 substantially in the same manner as in Figs. 1 and 2, and the cover plate 31 has a central aperture receiving the stud or spindle 32 projecting from the upper end of the cylinder. The top plate rests upon said upper post end, and may readily be lifted off the centering spindle 32 to allow substitution of the paper rolls as aforesaid.

In each of the illustrated species of my invention the paper roll is supported in vertical position with its bottom end resting and pressing by reason of the weight of the roll upon a fixed base plate, whereby rotation of the roll around the roll positioning cylinder or core is resisted; the assembled holder may also include a top plate which covers the central portion of the upper end of the roll and provides a more finished and pleasing appearance to the structure, and which, by reason of its own weight or by associated locking means, assists in securing the roll upon the holder and also in opposing rotation of the roll; and one or more parts of the holder may readily be separated from the remaining parts to permit the deposit or replacement of the paper rolls within the holder.

I claim:

A holder for a roll of paper comprising a base plate, a cylinder fixed in upright position upon the base plate and adapted to extend through an axially upright roll of paper having its lower end resting on the base plate, the cylinder having an axial recess extending downwardly from its upper end, a top plate having a depending tubular stem received within said recess, the cylinder and stem having registering apertures, and a spring having a locking detent releasably engaging within said registering apertures normally to prevent separation of the top plate from the cylinder, said top plate extending outwardly over a portion of the paper roll so that the roll is secured within the holder until the locking detent is released from engagement with the stem aperture to permit removal of the top plate, said engagement being releasable irrespective of the amount of paper on the roll.

Signed by me at Boston, Massachusetts,
this eighteenth day of March, 1929.

JOHN F. DUBY.
